JOHN S. LYONS, OF WILKES-BARRE, PENNSYLVANIA, ASSIGNOR, BY DIRECT AND MESNE ASSIGNMENTS, TO INTERNATIONAL LOCKING DEVICE COMPANY, A CORPORATION OF DELAWARE.

LOCKING DEVICE.

1,076,835.

Specification of Letters Patent. Patented Oct. 28, 1913.

Application filed April 29, 1912. Serial No. 693,875.

To all whom it may concern:

Be it known that I, JOHN S. LYONS, of Wilkes-Barre, Luzerne county, and State of Pennsylvania, have invented certain new and useful Improvements in Locking Devices; and I hereby declare that the following is a full, clear, and exact description thereof, reference being had to the accompanying drawings, which form part of this specification.

This invention is a novel lock especially adapted for locking the steering gear of automobiles, and yachts, but also applicable for the purpose of quickly and securely locking any relatively movable parts, as will be appreciated by those familiar with the art when the invention is once understood.

The object of the invention is to provide a lock having a bolt or plunger pin which may be easily and directly projected by hand so as to lock the parts, and when projected will be itself automatically locked in position so that it cannot be retracted or released until a key-operated controlling device is manipulated. The said controlling device may itself be a permutation or combination lock (preferably I employ a modified Yale lock) which will require a special key to operate it; so that when parts are locked by my invention it will be practically impossible to unlock or release same without a special key which cannot be readily duplicated.

Preferably I so construct my device that when the key-controlling device permits retraction of the locking bolt, the latter will be retracted instantly by a spring; I do not care to confine myself to a spring retracted locking bolt however as in some instances it might be desired to have my locking bolt both manually projected and manually retracted.

In order to impart a clear understanding of my invention I will now explain the same as embodied in an efficient form of lock,—especially adapted for locking the steering gear or shaft of automobiles, motor boats, and the like,—which will enable any one skilled in the art to fully comprehend the invention and its adaptability for other uses in the arts; it being understood that the invention is not restricted to the particular form and proportions of parts nor to the particular application indicated in the

drawings and described in detail in the appended specifications; I have summarized in the claims the essential features of the invention, and the novel parts and combination of parts of the lock illustrated in the drawings which I consider within the scope of my invention, for which I desire protection.

In said drawings—Figure 1 is a side elevation of the complete locking device applied to part of the steering shaft of an automobile for instance, the locking bolt being shown retracted. Fig. 2 is a front elevation of Fig. 1. Fig. 3 is a vertical central section through Fig. 1 or on the line 3—3, Fig. 2. Fig. 4 is a vertical section on line 4—4, Fig. 3. Fig. 5 is a view similar to Fig. 3 showing the bolt projected or in locking position. Fig. 6 is a vertical transverse section on line 6—6, Fig. 5. Fig. 7 is a horizontal section on line 7—7, Fig. 5. Fig. 8 is a detail view of the locking finger detached. Fig. 9 is a detail view of the bolt 1 detached.

As shown in the drawings A represents the steering shaft of an automobile or other vehicle, and B the sleeve in which said shaft is guided.

C designates the lock casing which in the present instance is shown as provided with a split yoke extension c adapted to surround the sleeve B and by which the casing is securely fastened to the sleeve by means of a clamping bolt and nut D as indicated in the drawings. This form of lock casing is of course a special form for the particular purpose for which the lock is shown as employed in the drawings. The form of the casing may be varied to suit the purpose for which the lock is to be used.

In the front part of the casing is a locking bolt 1, which is preferably mounted to slide longitudinally, in the casing C, and may be supported and guided at its front end in the front wall of the casing, and at its inner end in an opening 2^a in a plate 2 removably secured in the casing by a screw 2^b. For convenience of construction I preferably attach a hollow cap 1^a to the outer end of the bolt by means of a threaded socket engaging a threaded shank 1^b on the end of the bolt as shown. The part 1^a may be of brass or bronze, but I prefer to make the part 1 of hardened steel. It will be seen that the bolt 1 is movable at right angles to the sleeve

B and shaft A. The bolt is normally retracted so as not to interfere with the sleeve or shaft by means of a suitably arranged spring 3 which is preferably placed around the bolt 1 within a recess in the cap 1^a, and between the head of said cap and the plate 2. The spring 3 is a helical expansion spring and normally tends to retract the bolt to the position indicated in Figs. 1 and 2. The bolt or plunger pin can be projected into locking position by pushing it inward, preferably manually, against the resistance of spring 3 thereby putting it under compression as indicated in Fig. 5. In order to hold the bolt in its projected position I form in its under side longitudinal grooves 1^e which are separated by an intervening wall 1^f; and the grooves 1^e unite at their outer ends with a transverse groove 1^h in the bolt. Into the grooves in the underside of the bolt there are adapted to project locking fingers or dogs 4, which in the construction shown are preferably formed integral out of a strip of sheet steel bent upon itself as indicated in Fig. 8 so that the extremities of the locking fingers 4 tend to press toward each other but are normally held apart by the wall 1^f between the grooves 1^e, when the bolt is in retracted position. The locking fingers 4 may be confined in the casing by means of a pin 4^a engaging the bend of the metal strip and tapped into the casing, as shown, below, the bolt 1; the upper ends of the locking fingers 4 are preferably deflected as shown at 4^a so that said ends will lie partially within a slot 5^a in a plate 5 which is fastened within the casing by means of screws 2^b, 5^b, as shown, the upper end of plate 5 fitting over plate 2 and the opening or slot 5^a in the plate being elongated sufficiently to permit the passage of the bolt 1 therethrough as shown. The slot 5^a is of such width as will permit the locking fingers 4 to be sprung apart sufficiently to release the pressure upon the bolt rib 1^f and thereby allow the spring 3 to retract the bolt into the position shown in Fig. 3. The slot 5^a however prevents too great separation of the fingers 4 and will keep them in proper position for reengagement with the wall 1^f. When the bolt is projected the transverse slot 1^h in the bolt comes opposite the fingers 4 and the latter, if permitted, will close together within the slot 1^h and lie behind the inner end of the wall 1^f, which forms the locking abutment of the bolt, and when the bolt and fingers are in such position the bolt cannot be retracted because the fingers 4 lying behind the end of the wall 1^f absolutely prevent retraction of the bolt. When the bolt is retracted however as indicated in Fig. 3 the ends of the locking fingers 4 will press against the sides of the wall 1^f. Preferably I notch the forward ends of the wall 1^f slightly as at 1^g, so that when the bolt is

retracted the pressure of the spring fingers 4 will tend to hold the bolt in retracted position in addition to the action of the spring 3, thus preventing any possibility of the casual projection of the bolt by jarring of the lock casing, and also preventing rattling of the bolt; but the notches will not prevent the easy projection of the bolt by inwardly directed end pressure of the finger thereon.

From the foregoing it will be seen that in its normal position the bolt or plunger pin is retracted by the spring 3 and yieldingly held in such retracted position by said spring and locking fingers 4 engaging the notches 1^g in the sides of the wall 1^f; that the bolt can be readily projected into locking position by a push of the thumb or finger against the end of the bolt, or bolt cap 1^a; that when the bolt is projected into locking position as indicated in Fig. 5 the locking fingers 4 spring together in slot 1^g behind the end of the abutment or wall 1^f and positively lock the bolt in projected position; and that the bolt 1 cannot then be retracted unless in some manner the locking fingers 4 be separated or withdrawn from their bolt locking position. This separation of fingers 4 might be effected in various ways but I prefer,—for the purpose of safety and to prevent unwarranted tampering with or retraction of the bolt,—to employ a lock-controlled actuating device to release the fingers 4. As indicated in the drawings I preferably employ the rotary shaft of a cylinder, combination, or permutation lock and for this purpose I secure within the casing C, parallel with and below the bolt 1 and exterior to the locking fingers 4, a small cylinder lock 7, which may be of any approved construction; and which ordinarily comprises a rotary key-shaft 7^a and an internal set of tumblers that lock this key-shaft against rotation unless the tumblers are released by a specially designed key. This kind of permutation or combination lock is well known and I do not consider it necessary in the drawings to show any details of construction thereof, it being understood that such locks are of different construction and made to require individual keys. My present invention has nothing to do with the internal construction of such lock or any kind of cylinder lock, which I may wish to employ in its place. However in adapting such a lock to my invention I provide its key-shaft 7^a with an extension 7^b on its inner end, which extension may be flattened on opposite sides as indicated in the drawings and projects between the opposite locking fingers 4 when the parts are in assembled position. When the key-shaft 7 is turned so that its actuating key can be withdrawn, the end 7^b (which practically forms a double cam) then stands with its shortest diameter between the locking fingers 4, and will allow the upper ends of said locking fin-

gers 4 to meet, so if the bolt 1 is then projected into locking position the locking fingers 4 will lock said bolt as indicated in Figs. 5 and 7; and it will then be impossible 5 to retract the bolt 1 until the key-shaft 7 is rotated and this key-shaft 7 cannot be turned until the proper key is inserted in the key-way 7^a in said shaft 7. The kind of key used 10 is well known and therefore is not illustrated in the drawings. When the proper key is inserted and the shaft 7 turned, its cam head 7^b wedges or forces the locking fingers 4 apart until they clear the sides of the abutment 1^c on the bolt 1 whereupon the spring 3 15 retracts the bolt 1 (see Fig. 3) and it remains retracted until it is again forced inward.

What I claim is:

1. A lock comprising a bolt having parallel grooves and a locking abutment on its 20 under side, a pair of spring locking fingers engaging the grooves of the bolt and adapted

to engage the abutment to lock the bolt when projected, and devices adapted to separate the fingers to release the bolt.

2. A lock comprising a bolt adapted to be 25 manually projected into locking position, said bolt having parallel grooves on its under side, and a locking abutment at the end of said grooves; a pair of spring locking fingers engaging the grooves of the bolt and 30 adapted to engage the abutment to lock the bolt when projected; and rotary means adapted to separate the fingers to release the bolt; and a spring for projecting the bolt when released by the fingers. 35

In testimony that I claim the foregoing as my own, I affix my signature in presence of two witnesses.

JOHN S. LYONS.
